CLAIM

The ornamental design for a hockey stick, as shown and described.

DESCRIPTION

FIG. 1 is a perspective view of the hockey stick;
FIG. 2 is a side elevational view of the hockey stick;
FIG. 3 is a rear elevational view of the hockey stick;
and
FIG. 4 is a front elevational view of the hockey stick.
The side, rear, top and bottom surfaces are conventionally flat and unornamented.
